TARGET TOWING DEVICE

Otto J. Bratz, Adrian, Mich., assignor to American Chain & Cable Company, Inc., Bridgeport, Conn., a corporation of New York

Application May 17, 1944, Serial No. 536,002

2 Claims. (Cl. 28—78)

1

This invention relates to improvements in towing devices and more particularly to means for protecting target towing cables and for guiding targets onto a target carrier towed by an aeroplane.

In accordance with present day practice, targets of the "Wind-Sock" type are towed by cables upwards to 4,000 feet in length from an aeroplane travelling upwards to 100 miles per hour. The cable is stored on a winch in the aeroplane and its free end carries a target carrier and exchanger equipped with means for automatically releasing a used target by the oncoming new target. The free end of the cable is directly connected to the nose of the target carrier and exchanger. The targets are provided with rings passed over the cable and the rings are released one at a time as required.

The towing of the target through cross winds at the increased speeds of today causes the target to flutter and whip and go in all directions instead of following streamlined directly behind the aeroplane. The increase in speed is necessary to keep the present type of aeroplane in the air. Therefore the targets have to be towed at a much greater speed than previously. This causes oscillation and whipping due to the rapid movement of the target through the various air currents. This results in the heavy nose at the end of the cable whipping around even to a reverse position. If an exchange of targets is made under these conditions, and one cannot tell when these conditions will exist, the ring coming down at such tremendous speed with the target inflated will hit the nose cone at a sharp angle and sever the cable, resulting in the loss of the exchanger and target. Such oscillation and whipping may also be caused or accentuated by vibrations set up in the cable by the oncoming targets.

The main object of this invention is to provide means for preventing the formation of sharp bends in the cable at the point of or in the region adjacent to the carrier and exchanger, to provide a track and guide for the supporting ring of the oncoming target to permit it to continue its travel onto the carrier and exchanger, and to provide means which will lengthen the life of the towing cable and permit the towing to be performed at a greatly increased speed.

Other objects of this invention will appear from the following description taken in connection with the drawings, in which:

Fig. 1 is a diagrammatic view showing an aeroplane, a towing cable, a target carrier and ex-

2

changer, a target and the improvements of my invention.

Fig. 2 is a view of a target carrier and exchanger and the improvements of my invention on an enlarged scale; and

Fig. 3 is a longitudinal section through several of the vertebrae cones embodied in my invention.

Fig. 1 is a general diagrammatic view disclosing an aeroplane at 5 equipped with a winch indicated at 6 on which a towing cable 7 is stored and from which it is unreeled. The towing cable may be upwards of 4,000 feet in length and at its free end is equipped with a target carrier and exchanger generally indicated at 10 from which the target 11 to be towed is suspended.

In the known constructions the free end of the cable is directly connected to the nose of the target carrier and exchanger permitting the cable at this point to bend sharply when the target carrier and exchanger is whipped about due to any of a number of reasons.

The target 11 is preferably of the "Wind-Sock" type equipped with a ring 12 at its open end with which are connected four stretches of cable 13 connected by a single stretch of cable 14 with a ring 15. A series of targets equipped with such rings may be strung over the cable within the aeroplane and may be released one at a time, as required.

30 The target carrier and exchanger 10 as disclosed may include a cylindrical body portion or carrier proper 20 which may be provided with a nose 21 for guiding the ring 15 of a target onto the body 20 of the carrier. For the purpose of preventing rotative movement of the body 20 of the carrier from being transmitted to the towing line, the nose 21 is preferably connected to the body 20 by a rotatable ball bearing connection indicated at 22.

40 The exchanger mechanism mounted on the carrier body 20 may comprise a target ring retaining lever 24 provided with a retaining hook 25 at one end and reduced at its opposite end, as shown at 26, for cooperation with the forked end 45 of a tripping lever 27 which is spring drawn by a spring 28 into the position shown in Fig. 1. A restoring spring 29 is provided to restore the hook 25 into the position shown in Fig. 1 after the ring 15 of an oncoming target has passed over the lever 27. This construction is old and well known and is not a part of the invention disclosed and claimed in this application.

As disclosed in Fig. 1, the target carrier and exchanger and the target may move into the dotted line position and they may also move be-

yond this position which in the absence of my improvements would cause a sharp bend in the cable at the point of its attachment to the nose of the carrier and exchanger so that an oncoming ring would hit the nose of the carrier and exchanger or the bend in the cable causing the cable to be sheared on the edge of the hole in the nose of the carrier and exchanger. This figure discloses my improvements and shows the limit of the bending of the cable when my improvements are employed.

My improvements consist generally of a vertebral cone construction indicated at 30 surrounding the towing cable and connected to the nose 21 of the carrier and exchanger, as indicated in Figs. 1 and 2 and constituting a flexible extension for the nose of the carrier and exchanger. This construction may be thirty inches in length or longer and provision is made so that the relative pivotal movement of adjacent cones or sleeves is limited, preferably so as to limit the curvature of the cone construction as a whole to a twelve inch radius, as illustrated in dotted lines in Fig. 1. As disclosed in this figure, the ring of the oncoming target shown in dotted position is guided onto the cone construction or flexible extension 30 and onto the nose 21 of the carrier and exchanger 20.

By reference to Fig. 3 it will be noted that each cone generally indicated at 35 includes an enlarged body portion 36 which is provided with a socket 37 to receive the enlarged end 38 of the other end of an adjacent cone. This enlarged end is formed on the end of an extension or neck 39 formed on one end of the body portion 36 of the cone. The enlarged end 38 may be in the form of a ball and the forward end of the socket 37 may be correspondingly shaped, as indicated at 40. The socket is of greater length in the direction of the axis of the cone than the enlarged end 38 so that adjacent cones are permitted to move toward and away from each other, the most greatly separated condition being disclosed in Fig. 3, which is of less extent than the width of the ring 15.

The socket end of the body 36 is provided with a relatively wide flange 42, the interior diameter of which is slightly larger than the exterior diameter of the extension or neck 39, the relative inside diameter of the flange 42 and the outside diameter of the extension or neck 39 being so chosen that relative pivotal movement between adjacent cones will be limited, as disclosed in Fig. 3, which preferably is such that the entire cone construction cannot bend to a smaller radius of curvature than a twelve inch radius.

As is obvious from an inspection of Fig. 3, pivoting is limited by engagement of adjacent cones at the longitudinally spaced points 45 and 46, thus providing a very strong construction, and generally the cone construction is in a collapsed condition so that the distance between the points 45 and 46 in the direction of the length of the cone construction is greater than that disclosed in Fig. 3.

As disclosed in Fig. 3, the extension or neck 39 is provided with an axial bore 50 which is of slightly larger diameter than that of the cable and which is provided with a flaring end 51 to prevent any sharp bends in the cable as adjacent cones are pivoted, all as disclosed in Fig. 3.

The rearmost vertebral cone shown at 35a is provided with a cone-shaped bdy 36a from which

projects a screw threaded member 55 threaded into the nose 21 of the target carrier and exchanger. The end of the cable may be secured within the nose 21 by any suitable means as indicated at 56, as is well understood.

The cone 35b at the leading end of the cone construction or flexible nose 30 is preferably provided with a long tapered or cone-shaped nose 60, the end of which is of relatively small diameter so as to guide the ring 15 of the oncoming target onto the cone construction.

While I have illustrated and described a preferred embodiment of my invention, it is to be understood that I reserve the right to all changes and variations that fall within the principles of the invention and the scope of the appended claims.

I claim:

1. A protector for a cable comprising a plurality of concatenated sleeves each provided with a through-bore, the through-bore at one end being tapered to an intermediate point between the ends of the sleeve and having at that point a diameter slightly larger than that of the cable to be protected, said end of said sleeve being provided with a ball provided with an elongated neck connecting it to the body of the sleeve, the bore in said body being enlarged to provide a socket for cooperation with the ball of an adjacent sleeve, the other end of said sleeve being of cylindrical form and having a bore of slightly larger diameter than that of said neck to limit relative angular movement of adjacent sleeves, said ball being slightly smaller in diameter than said socket and free to move longitudinally therein, said socket having a greater dimension axially of said sleeve than said ball and said cylindrical end having a shorter length than the length of said neck.

2. A rope housing comprising flexibly connected sleeves interconnected by a ball and socket construction, one of said sleeves being provided with a ball-like end, the other of said sleeves being provided with a socketed end receiving and confining said ball-like end of said first mentioned sleeve, the socketed end having a cylindrical bore of a length to permit limited longitudinal movements of said sleeves relative to each other, the ball-like ends being free to move in said sockets, and a forwardly extending cylindrical flange on the outer end of said socketed end of slightly larger diameter than said first mentioned sleeve for limiting the pivotal movement between said sleeves, the bore of the sleeve having a ball-like end being tapered from a diameter substantially greater than that of the rope at the end to a diameter slightly greater than that of the rope intermediate the ends of the sleeve.

OTTO J. BRATZ.
